UNITED STATES PATENT OFFICE.

DAVID H. BLASCOW, OF MILWAUKEE, WISCONSIN, ASSIGNOR OF ONE-HALF TO GEORGE SYLVESTER, OF SAME PLACE.

STREET CARRIAGE-BLOCK.

SPECIFICATION forming part of Letters Patent No. 321,417, dated July 7, 1885.

Application filed May 19, 1885. (No model.)

To all whom it may concern:

Be it known that I, DAVID H. BLASCOW, of Milwaukee, in the county of Milwaukee and State of Wisconsin, have invented new and useful Improvements in Street Carriage-Blocks; and I do hereby declare the following to be a full, clear, and exact description of said invention, reference being had to the accompanying drawings, and to the letters or figures of reference marked thereon, which form a part of this specification.

My invention relates to a street carriage-block as a new and useful article of manufacture.

15 The object of my invention is to adapt the ordinary street carriage-block commonly in use as an aid in mounting a horse or stepping into a carriage to the additional use of a receptacle for ashes, refuse, &c., and to so 20 construct it that it will be strong, durable, and ornamental, and can be inexpensively made.

It is common, especially in cities, to have a carriage or horse block at the curbstone, and 25 also at the side of the street, near the house, a box or tank for ashes, refuse, &c., and by my invention I combine these two useful articles and utilize one and the same thing for both purposes, economizing cost and space 30 by constructing a receptacle for refuse that to the sight and in fact is a neat and attractive carriage or horse block, thus doing away with the unsightly and offensive refuse-receptacle commonly used.

35 My invention is illustrated by the accompanying drawings, in which Figure 1 is a perspective view of my device, showing the lid and the door to the discharging-aperture, both partially open. Fig. 2 is a sectional view 40 at right angles to the steps.

The same letters refer to like parts in both the views.

This carriage or horse block I usually construct either of wood or iron, and it is made 45 hollow, like a box or tank, and is provided on one or more sides with steps *a a*, with reference to its use as a carriage or horse block, and at the top with a lid, *b*, being the whole or a part of the cover of the receptacle, which 50 lid is hinged or removable, so as to allow of its being swung back or removed to permit of the pouring of ashes or refuse through the

opening, at other times covered by such lid, into the receptacle. On the rear side and preferably near the bottom is the hinged or 55 removable door or gate closing an opening into said receptacle, through which opening, when said door or gate is opened, the ashes or refuse may be removed from the receptacle. This door is kept closed by the buttons *d d*, or 60 equivalent means.

When I construct this block or receptacle of wood, I preferably furnish it with a sheet-metal lining, *e*, as shown in Fig. 2. The lid *b* may also be made self-closing by a coiled 65 spring, *f*, the two free ends of which are rigidly attached, the one to the under side of the cover and the other to the under side of the lid *b*.

It is obvious that my device makes when 70 closed a neat and ornamental carriage or horse block, and may at the same time be utilized as an ash and refuse receptacle; that ashes may be emptied into it through the opening covered by lid *b*, and may be readily removed through the opening at other times closed by the door *c*.

What I claim as new, and desire to secure by Letters Patent, is—

1. A carriage or horse block consisting of 75 a hollow receptacle having one or more steps on one or more sides, and provided with a lid-covered opening in its top and a door-closed opening on one side, near the bottom, and adapted for the reception of ashes or other 80 refuse, substantially as set forth.

2. A horse-block consisting of a hollow receptacle having one or more steps on one or more sides, and provided with a lid-covered opening in its top adapted for the reception 85 of ashes or other refuse, substantially as set forth.

3. In a horse-block, the combination of a hollow receptacle, *a*, having a discharging-aperture covered by door *e*, and an opening in 90 the top provided with the spring-closed lid *b*, substantially as set forth.

In testimony whereof I affix my signature in presence of two witnesses.

DAVID H. BLASCOW.
